Issued June 15, 1871

UNITED STATES PATENT OFFICE.

LOUIS SCHINDLER, OF ST. PETER, MINNESOTA.

DESIGN FOR BUCKLE.

Specification forming part of Design No. 5,053, dated June 27, 1871.

To all whom it may concern:

Be it known that I, LOUIS SCHINDLER, of St. Peter, in the county of Nicollet and State of Minnesota, have invented a new and original Design for a Buckle; and I do hereby declare that the following is a full, clear, and exact description thereof, which will enable others skilled in the art to make and use the same, reference being had to the accompanying drawing forming forming part of this specification, in which the drawing represents a perspective view of my improved buckle.

This invention relates to a new form of buckle, and consists in the application of an inner brace, whereby two loops are formed for the fastening of two straps, so that the buckle may be used for connecting three straps.

A in the drawing represents the surrounding-bar or body of the buckle, having a cross-piece, *a*, to which the tongue *b* is pivoted. On the back of the buckle—that is to say, opposite to the tongue—is arranged, in its body, a V-shaped inner brace, *B*, which forms two loops, *c c*. The point of the brace *B* may come in absolute contact with the body, or be disconnected therefrom, as shown. In the loops *c* two separate straps may be fastened, while a third is held by the tongue.

I claim as my invention—

The design for a buckle, as shown.

LOUIS SCHINDLER.
